UNITED STATES PATENT OFFICE.

WILLIAM C. WILLIAMS, OF DETROIT, MICHIGAN.

PAINT-CAN PRESS.

SPECIFICATION forming part of Letters Patent No. 379,190, dated March 6, 1888.

Application filed January 5, 1888. Serial No. 259,816. (No model.)

To all whom it may concern:

Be it known that I, WILLIAM C. WILLIAMS, of Detroit, in the county of Wayne and State of Michigan, have invented a new and useful 5 Improvement in Paint-Can Presses, of which the following is a specification.

My invention consists of an improved paint-can press, hereinafter fully described and claimed.

10 Figure 1 is a perspective with the lower end of one of the posts F broken away. Fig. 2 is a sectional elevation of the spring-nut and part of the screw-shaft, and Fig. 3 is a plan view of the bed-plate.

15 J represents a bed-plate, to which are secured upright posts F F, connected by a cross-head at the top, the whole being usually cast together.

20 C represents a hollow cylinder formed in the cross-head, in which is pivoted, at E, a thumb-lever, D, its lower surface having screw-threads 25 cut thereon, and its upper projecting end being pressed away from the cylinder C by the spring K, thus forming a spring-nut.

25 B represents a screw-shaft, on the upper end of which is secured a hand-wheel, A. The screw B passes through the cylinder C and its threads engage with the threads on the spring-nut D.

30 H represents a follower pivoted at G to the lower end of screw B, so that said screw can turn without necessarily turning the follower H, which is of the proper diameter to easily enter a paint-can.

35 L represent two lugs cast on one of the upright posts F, by which the press may be screwed to a wall or other vertical support, and the bed-plate J is provided with screw-holes, by which the press may be screwed to a bench or a table.

40 I represents a curved circular rim formed on the bed-plate J and extending any desired distance around the back of said bed-plate, and formed substantially on the same curve as the

outside of a standard paint-can, so that when the paint-can is set on the bed-plate J, with its 45 exterior in contact with the rim I, it is properly centered for the action of the follower H.

In operating my improved press the spring-nut D is opened against the action of the spring K with one hand and the screw B is raised 50 with the other hand until follower H is higher than the paint-can which is to be put into the press, thus avoiding the delay incident to raising the follower by rotating the screw B, and on releasing the spring-nut D the thread there- 55 on immediately engages with the thread on screw B and holds the screw and follower raised.

The paint-can having been placed on the bed-plate J, resting against the rim I, the follower H is lowered either by rotating the screw 60 B or by pressing the same down with sufficient force to open the spring-nut D, or by opening the nut with the thumb until the follower H rests upon the disk ordinarily used in paint-cans, when the paint may be pressed out by ro- 65 tating the hand-wheel A.

What I claim as my invention, and desire to secure by Letters Patent, is—

The herein-described paint-can press, consisting of the bed-plate J, provided with screw-holes for attachment to a bench or table, and having a curved rim, I, to center the can, the posts F, secured to said bed-plate and connected at top by a cross-head provided with vertical cylinder C, one of said posts being pro- 70 vided with perforated lugs L L, whereby it can be secured to a support, the screw B, passed through the cylinder C and provided with hand-wheel A and follower H, and the spring-nut D, pivoted in the cylinder to engage the 75 screw, substantially as described.

WILLIAM C. WILLIAMS.
